UNITED STATES PATENT OFFICE.

ISAAC D. SHIPPER, OF PHILADELPHIA, PENNSYLVANIA.

ELECTRIC WELDING FURNACE.

Application filed June 7, 1922. Serial No. 566,514.

To all whom it may concern:

Be it known that I, ISAAC D. SHIPPER, a citizen of the United States, residing in Philadelphia, Pennsylvania, have invented 60
5 certain Improvements in Electric Welding Furnaces, of which the following is a specification.

The object of my invention is to construct an electric furnace for welding metals, in 10 which the two metallic members are placed in the furnace with the abutting ends in a mold in which the fluid metal accumulates as it is melted from the members so that, on moving one member towards the other, the 15 union will be accomplished. The enlarged portion at the weld is reduced under a hammer as soon as the welded members are removed from the mold and while hot.

In the accompanying drawings:

20 Fig. 1 is a view of one end of my improved electric welding furnace;

Fig. 2 is a sectional elevation;

Fig. 3 is a view showing the upper section raised and illustrating the mold;

25 Figs. 4 and 5 are plan views of the lower portion of the furnace and illustrating the method of welding;

Fig. 6 is a perspective view illustrating the weld and the enlargement formed in the 30 mold; and

Fig. 7 is a view showing the completed weld after being reduced under a hammer.

Referring to the drawings, 1 is the base section of the furnace mounted on supports

35 2. In this section of the furnace is a hearth 3 of refractory material having a transverse groove 4 therein to receive the members to be welded. The groove is preferably shaped to receive the members properly so that 40 very little air will enter the furnace at the groove. The groove 4 is enlarged at the center of the furnace to form a mold 5 into which the metal flows as the ends of the members to be welded are melted, enlarging the members at the weld. This enlargement is reduced under a hammer after the 45 welded members are removed from the furnace.

50 6 is the upper section of the furnace connected to the base section by hinges 7 so that it can be raised on the hinges to permit the removal of the welded members. At the upper, front edge of the upper section 6 is an angle beam 8, in the present instance, to 55 which is attached an eye bolt 9. This eye bolt can be engaged by a hook of a hoist

when it is desired to raise the upper section 6. The upper section 6 is lined with refractory material 10, which encloses a chamber 11 directly above the mold 5 in 60 the base section. This chamber may be of any size desired, depending upon the size of the furnace and the material to be welded.

12, 12 are two inclined passages communicating with the chamber 11. 13 are the carbon electrodes. The inner ends of the electrodes terminate directly above the mold, as shown in Fig. 2, so as to heat the parts to be welded by radiation from the 70 arc struck between electrodes. As the chamber 11 is substantially closed, the metal is melted and fused in an atmosphere free from foreign gases and materials.

75 Any suitable means may be provided for feeding the carbon electrodes towards each other. Automatic means is preferred, but, in the present instance, independent feed screws 15 on brackets 16 are shown. These feed screws engage nuts 17 clamped to the electrodes 13. Each feed screw has a hand wheel 18. Surrounding the outer end of each passage 12 for the carbon electrodes is a water jacket 19 so designed that water will flow through the jacket, tending to 80 keep the electrodes cool.

85 20 is a peep hole inclined towards the mold so that the progress of the weld can be followed. This peep hole also allows certain gases to escape from the furnace.

90 The operation is as follows: *a*, *a* are two bars of metal to be welded. These bars are placed in the groove 4 in the base section of the furnace with their ends abutting over the mold 5. The furnace is then closed by lowering the upper section 6 and the electric circuit is applied through the carbon electrodes. The material is heated by radiation from the arc struck between the electrodes and the 95 ends of the bars *a*, *a* are melted—the metal flowing into the mold 5. One bar is then moved towards the other so as to close the gap. When the mold is filled, the electric current is cut off. After the metal has set, the upper section is raised, as in Fig. 3, and 100 when the welded joint has cooled sufficiently to allow the bar to be removed, it is transferred to a hammer and the enlarged portion *b*, Fig. 6, formed in the mold, is reduced, as in Fig. 7, and the bars are lengthened as desired. This is accomplished while 105 the bar is still hot.

This method requires only one heating of the bars to make a complete weld. In some instances, instead of moving one bar in respect to the other to close the gap, additional metal may be added, which will fill the mold. This metal will be incorporated with the metal of the bars, or other articles being welded.

If it be desired to enrich the metal at the mold, the material may be applied through the peep hole.

I claim:

1. The combination in an electric welding furnace, of a base section having a groove therein to receive the material to be welded, said groove being enlarged at the center of the furnace to form a mold; and an upper section having a chamber therein above the mold and also having passages therein for the carbon electrodes which terminate directly above the mold.
2. The combination in an electric welding furnace, of a base section having a groove entirely across the furnace to receive the articles to be welded, said groove being enlarged at the center to form a mold; an upper section hinged to the base section at one side so that it can be raised to remove the welded articles, said upper section hav-

ing a refractory lining forming a chamber 30 directly above the mold in the base section; and carbon electrodes carried by the upper section and terminating in the chamber above the mold.

3. The combination in an electric furnace, 35 of a base section; a transverse groove therein, said groove being enlarged to form a mold; an upper section movable in respect to the lower section and having a chamber therein located above the mold; and two inclined carbon electrodes extending into the chamber in the upper section of the furnace and terminating above the mold, the upper section being lined with refractory material 40 and the base section having a hearth of refractory material in which the groove and the mold are formed.

4. The process herein described of welding two metallic articles, said process consisting in placing the articles end to end, reducing the abutting portions of the articles to a fluid by an electric arc, molding the fluid metal to form an enlargement, stopping the melting process, allowing the metal to cool until it sets, and, while the metal is hot, 50 reducing the enlargement produced by molding.

ISAAC D. SHIPPER.
